UNITED STATES PATENT OFFICE.

HENRY D. DEAM, OF BENTON HARBOR, MICHIGAN.

SALVAGING APPARATUS.

1,338,816.

Specification of Letters Patent.

Patented May 4, 1920.

Application filed May 6, 1918. Serial No. 232,677.

To all whom it may concern:

Be it known that I, HENRY D. DEAM, a citizen of the United States, residing at Benton Harbor, in the county of Berrien 5 and State of Michigan, have invented certain new and useful Improvements in Salvaging Apparatus, of which the following is a specification.

This invention relates to salvaging sunken 10 ships, boats, and other property; and has for its object providing suitable apparatus and methods for applying or attaching the apparatus to the sunken objects and raising them to the surface. When boats sink 15 in deep water, and especially if the bottom of the sea is muddy, as is often the case, it is a difficult matter to attach to the boat apparatus which will not pull loose when the attempt is made to raise the boat. In view 20 of this I provide apparatus comprising special means for gripping or connecting to the boat.

Of the accompanying drawings, Figure 1 is a general view of apparatus attached to 25 a boat, and means for elevating the boat, which embody the features of my invention. Fig. 2 is a plan view of a ring used in connection with the apparatus; and Fig. 3 is a section of the ring along the line 6—6 30 of Fig. 2.

In raising sunken boats it becomes desirable to attach apparatus to the boat at various points, so as to keep the boat from listing too much, or to tilt it in various ways 35 in order to prevent the apparatus from slipping or breaking away from the boat.

Assuming the sunken boat 10 is not too deeply embedded in the mud, I first pass under the bow 11 and the stern 12 the respective cables 13 and 14. Any suitable 40 method may be used in placing these cables. The cables may be dragged on the ground, by the scows 15 and 16, until the cables pass under the end of the boat. Or divers or 45 salvaging submarines may be used to assist in putting the cables in place. Having placed the cables the four ends are brought together in one of the scows and passed up through an opening 17, and each pair of 50 cables is attached to any suitable elevating means such as the windlasses 18 and 19. A hinged ring 20 is then opened by removing the bolt 21, closed around the four cables, and locked closed by replacing the bolt, and 55 the ring is allowed to slip downwardly on the cables. Fixed to this ring is a cord 22

which serves as a means for indicating the depth to which the ring descends, and which may be used to raise or to assist in lowering the ring. The purpose of the ring is to hold the cables together so as to prevent 60 them from slipping off the boat, and for this reason the depth to which the ring descends on the cables is important. Teeth 23 are provided on the rings to prevent them from slipping upwardly when tension is applied 65 to the cables to raise the boat.

A second pair of cables 24 and 25 is then applied to the boat in a similar manner and connected to another scow 26, or to another portion of the same scow; so as to control 70 the tilting of the boat, and thus prevent any of the cables from slipping.

When the boat has been lifted from the ground it may happen that some of the lifting means begin to yield, or for 75 some reason are deficient; or other lifting means may be necessary. In such an event cables 46 may be passed under the boat, with rings 20 holding the cables 80 snugly against the sides of the boat. The boat will then be firmly held and can be raised to a height where it can be floated by the use of any suitable means. The means which I prefer for floating the boat, 85 and, if desired, for assisting in lifting the boat, are fully described in my copending applications Serial Nos. 223136 and 228292, filed, respectively, March 18, 1918, and April 13, 1918. If the suction on the boat 90 due to mud is excessive, any suitable means, such as suction dredges, may be used to reduce the suction, and thus assist the elevating means.

I claim as my invention:

1. Boat salvaging means comprising a buoyant member, pulling means supported by said member, a cable passing from said pulling means downwardly and around a boat to be raised and back to said buoyant member, and means slidably encircling the two cable strands above said boat, said means comprising a ring having teeth on one side, said teeth arranged to prevent slipping of the ring on the cable. 95 100 105

2. Boat salvaging means comprising a buoyant member, pulling means supported by said member, a cable passing from said pulling means downwardly and around a boat to be raised and back to said buoyant member, means slidably encircling the two cable strands above said boat, and means 110

to prevent said encircling means from slipping upwardly on said cable strands when said pulling means is operated.

3. Boat salvaging means comprising a buoyant member, pulling means supported by said member, a cable passing from said pulling member downwardly and around a boat to be raised and back to said buoyant

member, clasping means slidably encircling the two cable strands above said boat, and means for determining and controlling the distance said clasping means slides downwardly on said cables.

In testimony whereof, I hereunto set my hand.

HENRY D. DEAM.
